ELECTRIC SOURCE DEVICES FOR FIRE ALARM SYSTEMS

This invention relates to improvements in electric source devices for fire alarm systems.

Electric sources for fire alarm systems wherein their fire sensing means utilize fire detecting elements which sense occurrence of fire hazards by the variation in voltage across the elements, for example an ionization chamber and the like, generally require a suitable voltage stabilizer to maintain the sensitivity of the fire detecting elements at a definite value, in order to provide constant supervision.

In a prior source for a fire alarm system of the type referred to above, as the source is also used to energize lamps for indicating the operation of the fire alarm system and/or to energize a receiver thereof, the stabilized source is required to have sufficient capacity to satisfactorily operate the fire alarm system when a fire occurs. For this reason the source for a fire alarm system is required not only to be stable but also to have a large capacity, thus increasing the cost thereof.

The object of this invention is to decrease the capacity of the source. According to this invention in a fire alarm system comprising a fire sensing means including a fire responsive element which senses a fire hazard by varying the voltage thereacross and a fire indicating means, and a receiver including a stabilized source for supervision, means to receive a signal from said fire sensing means and a fire alarm means, there is provided an electric source device characterized in that upon occurrence of a fire hazard said signal receiving means operates to disconnect the stabilized source from the fire sensing means and to connect an independent source to the fire indicating means and to the fire alarm means.

This invention can be more fully understood from the following detailed description when taken in conjunction with the accompanying in which:

FIG. 1 shows a connection diagram of one example of an electric source device for a fire alarm system embodying this invention and

FIG. 2 shows a modified embodiment of the electric source device for use in a receiver.

Referring now to the accompanying drawing, FIG. 1 shows a circuit diagram of a fire alarm system embodying this invention and comprising a fire sensing means A, a receiver B and supply lines l^1 and l^2 interconnecting them. Fire sensing means A comprises a fire responsive element T which may be an ionization chamber, for example, connected to supply lines l^1 and l^2 at its terminals 1 and 2, respectively, a controlled rectifier S with one terminal connected to line l^1 , and a parallel combination of a lamp L1 and a protective resistor R1 connected between the other terminal of the controlled rectifier and line l^2 . Receiver B comprises a stabilized source E3 adapted to normally supply a stabilized voltage for supervision across lines l^1 and l^2 via a relay contact $h2$ and a relay G which receives a signal from the fire alarm system in a manner to be described later, and a series circuit connected across lines l^1 and l^2 and including a normally opened relay contact $h3$, a resistor R2, a push button P1 and a source E2 for said pilot lamp L1. The receiver also includes a source E1 for energizing relay circuits and an alarm device. A series circuit including an alarm buzzer b and a normally opened contact $h5$ and series circuit including an alarm lamp L2 and a normally opened contact $h4$ are respectively connected across source E1. An alarming relay H is provided with its one end connected to the negative terminal of source E1 and the other end to parallel connected normally opened contacts $h1$ and g . A push button P2 interlocked with said push button P1 is included as shown. It is to be understood that contacts $h1$ through $h5$ are operated by the alarming relay H while contact g is operated said receiver relay G.

The fire alarm system operates as follows:

When fire responsive element T detects the occurrence of a fire, it will supply a signal to the gate electrode of the controlled rectifier S from its output terminal 3. Thus the controlled rectifier S becomes conductive to light pilot lamp L1

through a circuit from stabilized source E3 via receiver relay G, contact $h2$, line l^1 , controlled rectifier S, lamp L1 and protective resistor R1, and line l^2 , whereby to indicate the position in which the fire took place. Concurrently therewith the receiver relay G in the receiver B is energized to close its contact g , thus energizing alarming relay H from source E1. As a result its contact $h2$ is opened whereas contacts $h1$, $h3$, $h4$ and $h5$ are closed and the alarm relay H is self-hold by contact $h1$. Opening of contact $h2$ and closure of contact $h3$ transfers the source for pilot lamp L1 of the fire detecting means A from source E3 to source E2 thus continuing the lighting of the pilot lamp L1. Contact $h2$ and $h3$ are designed to operate such that contact $h3$ is closed before opening contact $h2$, thus assuring continuous energization of the fire detecting means A. Closure of contacts $h4$ and $h5$ results in the energization of buzzer b and alarm lamp L2 from source E1. Thus, it will be seen that source E2 is required to have a capacity only sufficient to maintain the controlled rectifier S in the fire detecting means A in the conductive state and to light pilot lamp L1. In addition, the source E2 should have a sufficiently flat voltage. On the other hand, source E1 may be a direct current source which may fluctuate to some extent so long as it can continuously operate alarm relay H.

FIG. 2 illustrates a modified construction of the receiver which is identical to that shown in FIG. 1 except that a single source E2 is utilized for energizing both pilot lamp L1 and the alarm device in the receiver. However, since the modification shown in FIG. 2 operates in the same manner as that shown in FIG. 1, it is believed unnecessary to describe it again.

While in the above described embodiments only one fire detecting means A is connected to one circuit comprised by lines l^1 and l^2 , it will be clear that any desired number of fire detecting means may be connected to one line. Similarly, the stabilized source E3 may be used commonly for a plurality of circuits.

Thus, according to this invention, the stabilized source is used only to sense the occurrence of the fire hazard and this source is automatically switched to other source for providing indication and alarm of the fire so that the stabilized source is required to have a small capacity only sufficient to supply a small current during normal supervision. In addition, as the current required for normal supervision is small a plurality of fire alarm systems can be connected to a single stabilized source. Thus, this invention makes it possible to greatly reduce the capacity of the stabilized source which is required to operate a sensitive fire detecting element in the fire alarm system.

What is claimed is:

1. A supervisory fire alarm system comprising:
a fire sensing station having a pair of line terminals normally substantially open circuited and across which are connected
an ionization chamber and
a signal controlled rectifier responsive to detection current flow in said ionization chamber to conduct current between said line terminals;
2. A receiving station connected to said line terminals of said fire sensing station and including
a stabilized voltage source, current responsive means, and a circuit connecting said source through said current responsive means to said line terminals to supply stabilized operating voltage from said source to said ionization chamber and said controlled rectifier;
3. An electric power source,
alarm means,
an alarm relay with latching contacts connected to said power source, and
a circuit connecting said power source to energize said alarm means when said alarm relay is energized;
4. A switch means operated by current flow from said stabilized voltage source through said current responsive means to said controlled rectifier for energizing said alarm relay; and

3,623,050

3

4

switch contacts operated upon energizing said alarm relay
to supply current to said line terminals from said power
source and to disconnect said stabilized voltage source
from said line terminals.
